PHOTOSCULPTURE

Sidney Thomas Jeffreys and Henry John Petty,
Newport, England, assignors to Photosculpture
Limited, Newport, England, a British company

Application October 14, 1936, Serial No. 105,529
In Great Britain October 16, 1935

2 Claims. (Cl. 88—24)

This invention relates to the production from a photographic record of models, copies or enlargements of the subject photographed, in solid material, such production being generally known as photo-sculpture. The invention has reference to improved means for the production from photographs, of copies of the original either enlarged, reduced, or of corresponding size and in solid material, and is more especially concerned with the reproduction by photographic means of "plane surfaces", e. g. surfaces having ornamentation, decoration or the like in the same or approximately the same plane, or plaques in relief or intaglio. Generally the invention has reference to the method of and apparatus for photosculpture as set forth in the specification of our British Patent No. 254,791.

The invention described in our British Patent Specification No. 254,791 relates to the production from photographs of models, images, busts or the like by a method in which during the photographic process the subject revolves, or alternatively the photographic apparatus is made to revolve about the subject, and in the process of reproduction the block from which the model is produced rotates step by step relative to the cutting tool, or alternatively the cutting tool revolves step by step about the axis of the block.

According to the present invention a photographic record may be made of a "plane surface" in the following manner, viz:—

The method of photography and the photographic and lighting apparatus are substantially as described in British Specification No. 254,791, but according to this invention instead of the relative movements of the subject or object and the said apparatus being rotary, the apparatus is caused to travel parallel to or at a known angle to the surface of the object photographed, or alternatively the subject is caused to move across before the photographic and lighting apparatus in a straight line at right angles or a known angle to the beam of light projected by the lighting apparatus.

By present methods of photosculpture photographs are taken of the subject to be reproduced which record the outline of sections of the subject, such sections according to the method described in our prior British Specification No. 254,791, being taken axially and through a common centre of the subject and according to the method described in the specification of our co-pending British application No. 28,627 of 1935 such sections are taken radially from two or more points about the circumference of the subject.

This invention relates to a method particularly suitable for dealing with recording photographically the shape and outlines of sections of subjects in relief or intaglio and upon a plane surface and from the photographic records so produced, or from guide sheets produced therefrom a model or copy of the subject may be reproduced from solid material.

The general method of obtaining the photographic record as described in the specification of our British Patent No. 254,791 is utilised in this invention, namely; a beam of light is projected upon the subject, such beam being partially intercepted by a preferably straight edged screen (the edge of which preferably cuts the axis of the lens of the light projector) in such a manner that a sharply defined outline or profile is exhibited upon the subject as a shadow in a preferably vertical plane.

Whatever may be the shape of the subject, such shadow when viewed along the axis of the projector lens, appears as a straight line or a line corresponding to the edge of the screen and such shadow falls upon every surface of the subject in the same vertical plane and visible from the projector lens. In other words it follows the outline of a section of the subject taken at a known angle. When viewed from an angle in the same horizontal plane as the axis of the projector lens the shadow appears (if the subject is of irregular outline) as an irregular line representing a true or foreshortened view of the outline of the section of the subject, according to the angle from which the shadow is observed.

A photographic camera is angularly spaced from the source of the beam of light, the angle between the axis of the projector lens and the optical axis of the camera lens being known and being hereinafter referred to as the "light photo angle", and is operated to take a series of photographs of the shadow as the shadow is caused to traverse the surfaces of the subject as herein-after described, thus recording the outline of sections of the subject at known positions taken vertically and in parallel planes.

A camera and light projector are mounted upon a table (which table with the camera and projector thereon are together hereinafter included in the term "recording apparatus") which table is adapted to travel preferably horizontally and parallel or at a known angle to the surface of the subject in such a manner that the beam of light first falls on one extremity of the surface of the subject and during the movement of the recording apparatus travels across the surface of

the subject (and preferably at right angles thereto) to the opposite extremity.

The camera is angularly spaced from the projector so that the respective axes of the projector lens and the camera lens (the angle between which is hereinafter called "the light-photo angle") intersect at or near the surface to be photographed.

During the movement of the recording apparatus a series of photographs is taken by the camera (the mechanism of which is suitably connected with the movement of the recording apparatus) which record the shape of the shadow at a known number of points, each photograph taken recording the shape of the outline of a vertical section of the subject taken along the line of the beam of light and at the point where it faces upon the subject at the time the photograph is taken. By this method a record is obtained of the outlines of any desired number of vertical sections of the subject taken at known positions and in parallel planes.

By a modification of this invention, instead of the recording apparatus moving, the subject may be placed upon a stand which makes the same relative movement in regard to the recording apparatus.

To facilitate accurate projection or setting of the outlines so obtained (or of guide sheets or templates prepared therefrom) in the reproducing machine a depth indicator may be used during the photographic process on which the beam of light falls at preferably all points of its travel and the object of which is to enable a record 35 to be made on the photographic record of each outline of a point a known distance from the recording apparatus.

The depth indicator consists of a strip having a vertical surface, horizontally placed at right angles to the beam of light and above or below 40 the subject and in a position at, or at a known distance behind, the point of intersection of the axes of the projector and camera lens, and as more particularly described hereinafter with reference to the accompanying drawings.

The apparatus for reproducing the models comprises a control screen upon which the photographic records of each outline or guide sheets prepared therefrom (either of which are herein 50 after included in the term "recorded outline") are optically projected or otherwise placed in position (the recorded outlines being corrected to their true proportions if desired according to the method described in our prior British Specification No. 254,791) in a cutting or sculpturing machine adapted to cut or inscribe in a block of solid material an outline corresponding in shape to any sectional outline appearing on the control screen and in the same position relative to 55 the block as the sectional outline appeared in the original subject when photographed.

The operation of the reproducing machine may be in part mechanical and in part manual, or may be entirely automatically controlled according 60 to the method described in the specification of the pending British application of the above-named Sidney Thomas Jeffreys No. 14,382 dated May 21, 1936.

In order that the said invention may be clearly understood and readily carried into effect, the same will now be further described with reference to the accompanying drawings in which:—

Figure 1 represents in front elevation a subject upon a stand in position to be photographed.

Figure 2 represents in plan the subject as in Figure 1, and a simple form of recording apparatus.

Figures 3 and 4 represent in side elevation and plan respectively a simple form of reproducing apparatus.

The subject 1 is placed in a suitable position before the table 2 carrying the recording apparatus.

The recording apparatus comprises a light projector 3 and a cinematographic camera 4 angularly spaced upon a travelling platform 5. The projector 3 is so mounted that the optical axis of its lens is at right angles to the direction of travel of the platform 5 and so that the light- 15 photo angle 6 between optical axes of the lenses of the projector 3 and the camera 4 is known and so that the said axes intersect at a point 7 near the surface of the subject 1.

The projector 3 is adapted to throw a beam 20 of light 8 upon the subject 1 such beam being partially interrupted by a straight edged screen in such a manner that a sharply defined vertical shadow is projected upon the subject 1 and the depth indicator 9 hereinafter described. To eliminate unwanted light the beam may be intercepted by a second screen so that in effect a narrow vertical beam of light is projected.

Such beam when viewed along the axis of the projector lens appears as a straight vertical line 30 whatever may be the contour of the surface of the subject, but when viewed from an angle, appears (if the contour of the subject is irregular) as an irregular line as illustrated by the line 10, such line representing a foreshortened outline of 35 a section of the subject 1 taken vertically along the line of the beam 8, the degree of foreshortening depending upon the angle at which the line is viewed.

The platform 5 is adapted to travel horizontally 40 along the table 2 its movement being operated by the threaded rod 11 which is steadily rotated by the pinion wheel 12 and during its movement the beam 8 traverses the surface of the subject 1. During the movement a known number of 45 photographs is taken by the camera 4 recording the varying shape of the line 10 at known intervals during the travel of the beam 8 across the subject, in this manner photographically recording the outline of sections of the subject at a 50 number of known positions.

The operation of the camera 4 is preferably synchronised with the travelling movement of the platform 5 for instance by the rotating square section rod 14 operated by the pinion wheel 13 55 which is in mesh with the pinion wheel 12. Mounted on the square section rod 14 and rotating with it is a sliding pinion 15 which is adapted to travel with the platform 5 and which engages with the pinion wheel 16 which is connected with the camera mechanism by the shaft 17.

To facilitate accurate projection or setting of the recorded outline in the reproducing machine a depth indicator 9 is mounted above the subject 1 and parallel to the direction of travel of the platform 5, and in such a position that the beam 8 falls upon it during the whole of its travel; the surface of the depth indicator being vertically above or a known distance behind 65 the deepest re-entrant surface of the subject 1.

Upon a table 18 (Figures 3 and 4) is mounted a frame 19 in which is fitted the control screen and a tool carrier 21, the tool carrier being adapted to travel vertically upon guides 22, its 70

75

movement being controlled by a threaded shaft 23 which engages in a nut in the tool carrier 21, the threaded shaft being rotated either steadily or intermittently by the pinion 24. Mounted on the tool carrier 21 is a drilling or cutting tool 25 attached to a sliding member 26.

The sliding member 26 is carried in guides or slots in the tool carrier 21 and is adapted to move horizontally in the directions corresponding with 10 the feeding or withdrawal movement of the cutting tool 25.

The cutting tool may, according to the nature of the substance from which the model is to be reproduced, be either a graving or a drilling or 15 milling tool; in the latter case the drill or milling tool may be operated by an independent motor mounted on the sliding member 26, by a flexible drive 33 or by other suitable means.

The feeding and withdrawal movement of the 20 cutting tool is controlled by the sliding member 26, which through the bevel pinions 27 rotates the square section shaft 28, upon which is fitted a sliding pinion 29 adapted to follow the vertical movement of the tool carrier 21, and which engages with a rack 30 fitted to the sliding member 26.

Attached to the sliding member 26 is a pointer or line following device 31 touching or in close proximity to the surface of the control screen 20

30 and moving in unison with the cutting tool 25.

Also mounted on the table 18 is a sliding table 32 adapted to be moved horizontally intermittently and by known degrees in a direction at right angles to the feeding and withdrawal movement of the cutting tool 25, the horizontal movement being operated by the handle 34 and threaded shaft 35 which engages in a nut fitted beneath the sliding table 32.

Engraved or marked upon the control screen 40 20 is a setting line or mark 36^a so placed that when the pointer 31 coincides with it the cutting tool 25 is at the limit of its feeding stroke.

In order to reproduce a model from the recorded outlines a block of suitable solid or plastic material 36 is placed and rigidly fixed upon the table 32, the table being set in position by the rotation of the handle 34 at or near one extremity of its movement and so that the cutting tool 25 will inscribe its first cut at a suitable position near one extremity of the block 36.

Assuming that the recorded outlines of the subject 1 have been taken from left to right across the surface of the subject and it is intended to project or place them on the control screen 20 in 55 the same order, then at the commencement of the reproduction process the block 36 will be positioned in relation to the cutting tool 25 so that the cutting tool will in its first cutting operation enter the block 36 at or near its left extremity when viewed from the cutting tool.

The first recorded outline is then optically projected on the control screen 20 in the manner described in the previous British Specification No. 254,791, the foreshortening being optically corrected, (either fully or partially according to whether a true or corrupted reproduction is required) by the method described in the said previous specification, or, if a guide sheet has been prepared from the photographic records, the same is placed in position on the control screen, and in either case so that the image 37 of the depth indicator 8 coincides with the setting line or mark 36^a.

The vertical movement of the tool carrier 26 is

then commenced and continues either steadily or intermittently to the end of its travel, the pointer 31 being caused to follow the outline 38 appearing on the control screen 20 by the operation of the handle or crank 26^a. It will readily be seen that during this movement the cutting tool 25 will inscribe a line in the block 36 corresponding in shape to the outline 38 appearing on the control screen.

The next recorded outline is then similarly 10 projected or placed upon the control screen and the table 32 moved horizontally so that the second outline may be cut in its appropriate position on the block 36.

If the model to be reproduced is to be on the 15 same scale as the original, then the recorded outlines projected or placed upon the control screen will be projected or placed true to scale, and between the cutting of each outline the table 32 and block 36 will be moved (if the model 20 is to be reproduced in true proportion) the same distance as the beam of light 8 travels between each successive photograph in the photographic process, that is to say, if during each inch of travel of the beam of light 8 forty photographs 25 are taken by the camera 4 in the reproduction process, the table 32 will be moved one fortieth of an inch between the cutting of each outline in succession.

If the reproduction is on an enlarged or reduced scale the recorded outline projected or placed upon the control screen 20 may be optically enlarged or reduced in projection (or enlarged or reduced guide plates placed in position) and in this case the movement of the table 32 35 between each successive cutting operation will be proportionately increased or diminished.

What we claim and desire to secure by Letters Patent of the United States is:

1. Apparatus for obtaining a record of the 40 surface contour of a tablet-like object comprising an object holder, a platform movable in a path horizontally parallel past the face of the object, a light projector and a camera mounted on said platform with their optical axes at an 45 acute angle to each other and directed toward said object, said axes converging to a point adjacent said object, means in said projector for casting a vertical shadow line on said object, and means for operating said camera to take pictures 50 of said object and shadow line thereon as said platform is moved horizontally in a path parallel to said object.

2. An apparatus for obtaining a record of the 55 surface contour of a tablet-like object, including a platform movable horizontally past the object, a light projector mounted on said platform and directed towards the object, an intermittently operated photographic camera also mounted on said platform and disposed with its optical axis 60 at an acute angle to the axis of the light beam from the projector, means for casting a shadow line upon the object and means for producing parallel rectilinear movement of the light beam and camera relative to the object while taking 65 successive photographs of said shadow line, wherein the light projector and the camera are mounted, a screw operatively engaging with the platform to move it, and mechanism driven by said screw for operating the camera intermittently in synchronization with the movement of the platform.

SIDNEY THOMAS JEFFREYS.
HENRY JOHN PETTY.
